UNITED STATES PATENT OFFICE.

THOMAS C. WURTS, OF PITTSBURGH, PENNSYLVANIA, ASSIGNOR TO WESTINGHOUSE ELECTRIC AND MANUFACTURING COMPANY, A CORPORATION OF PENNSYLVANIA.

CONTROL APPARATUS.

1,347,885.

Specification of Letters Patent. Patented July 27, 1920.

Application filed January 16, 1917. Serial No. 142,642.

To all whom it may concern:

Be it known that I, THOMAS C. WURTS, a citizen of the United States, and a resident of Pittsburgh, in the county of Allegheny and State of Pennsylvania, have invented a new and useful Improvement in Control Apparatus, of which the following is a specification.

My invention relates to control apparatus and especially to controllers of the drum type that are adapted for a double function, such as the control of accelerating and regenerative circuits or of circuits for effecting a forward and reverse operation of one or more motors.

The object of my invention is to provide a device of the above-indicated character which shall be relatively compact and simple in construction and effective and reliable in operation and which shall perform the desired function of governing two different sets of circuit connections through the agency of a single operating handle.

In another aspect, it is the object of my invention to provide a plurality of vertically aligned control drums embodying a relatively simple mechanism for rendering the rotative movement of the drums mutually exclusive, and a common handle for effecting the movement of either drum, in accordance with the will of the operator, without requiring any readjustment or substantial change in the initial location of the operating handle.

My invention may best be understood by reference to the accompanying drawing, wherein Figure 1 is a view, in elevation, of a control apparatus constructed in accordance with my present invention; Fig. 2 is a developed view of an interior portion of the upper half of the control apparatus; Fig. 3 is a similar view of a corresponding interior portion of the lower half of the device; and Fig. 4 is a transverse sectional view taken on the plane IV—IV of Fig. 1.

Referring to the drawing, the apparatus shown comprises a plurality of control drums 1 and 2, of a familiar type, that are arranged in substantially vertical alinement; a hollow shaft 3 which extends through both drums and loosely rotates therewithin, the lower end of the shaft 3 being located in a suitable stationary bearing member 4; a rod 5 which is loosely positioned within the hollow shaft 3 and projects beyond the upper end thereof for a purpose to be de-

scribed; a suitable operating handle 6, of a familiar type, that is rigidly associated with the upper end of the hollow shaft 3; and a disk or knob 7 that is fixedly attached to the upper end of the rod 5.

As stated above, the drums 1 and 2 may be employed for any desired control purposes, such as the control of accelerating and regenerative circuits of one or more motors. Such adaptation of the drums is indicated by a plurality of stationary control fingers 10 which are engaged by suitable contact segments 11 of the drum 1 when moved through its successive operative positions *a*, *b*, etc., in a clockwise direction, as indicated by the corresponding arrow. An annular slot 12 surrounding the hollow shaft 3 is located in the central interior portion of the drum 1 and is provided with an upwardly-extending recess 13, more clearly shown in the developed view of Fig. 2, within which a lug or projection 14 of the rod 5 normally rests, as illustrated. The wall of the hollow shaft 3 is provided with a corresponding slot.

The other or regenerative control drum 2 is likewise provided with a suitable number of stationary control fingers 20 and movable coöperating contact segments 21 for engaging the control fingers 20 upon movement of the drum 2 through its successive positions *a'*, *b'*, etc., in a counter-clockwise direction, as indicated by the corresponding arrow. An annular interior slot 22, corresponding to the previously described slot 12 and having a downwardly extending recess 23, best shown in Fig. 3, is provided, and a second lug or projection 24 of the shaft 5 normally reposes within the slot 22 just above the recess 23, as illustrated in Fig. 1. The hollow shaft 3 is provided with a slot that registers with the drum slot 22 and the recess 23. The relation of parts at this time is clearly shown in Fig. 4.

For the purpose of normally biasing the rod 5 into its illustrated upper position, a suitable helical spring 25 is located within an interior recess near the lower end of the hollow shaft 3 and supports the lower end of the rod 5.

To insure that both the control drums shall not be simultaneously operated, even through the sticking or frictional engagement of certain parts, a plurality of suitable stationary arms or stop members 26 and 110

27 are properly located with respect to the drums 1 and 2 to prevent counter-clockwise and clockwise movement thereof, respectively.

- 5 Inasmuch as the type or specific location of the coöperating stationary and movable contact members is immaterial to my present invention, I have not deemed it necessary to fully illustrate or describe a construction which is familiar to those skilled in the art, and it will be understood that any desired disposition of such contact members may be employed.

Assuming that the various parts occupy the illustrated positions, which correspond to the normal or "off" position of both control drums, the clockwise rotative movement of the upper drum 1 may be effected by corresponding rotative movement of the

20 operating handle 6, whereby the hollow shaft 3 engages the lug 14 of the rod 5 which lug, in turn, engages the side wall of the interior drum recess 13, whereby the desired movement is imparted to the control drum

25 1. Any degree of forward or backward movement of the control drum 1 may thus be produced by correspondingly actuating the operating handle 6. In the meanwhile, the other lug 24 of the rod 5 travels within the

30 drum interior slot 22 and the corresponding slot in the wall of the hollow shaft 3, and no movement of the regenerative control drum 2 occurs. As previously stated, any accidental movement of the drum 2, through the

35 agency of undue friction, etc., is effectively precluded through the use of the stop member 27.

Assuming that the various controller parts occupy the illustrated positions and that it is desired to effect operation of the lower control drum 2, the knob 7 may be pressed downwardly in opposition to the action of the spring 25 and given a slight turn in the counter-clockwise direction, whereby the

45 upper lug 14 of the rod 5 enters the interior slot 12. Thus, the rod 5 is held in its lower position, wherein the lower lug 24 of the rod 5 rests within the interior recess 23 of the drum 2.

50 Upon a continued or subsequent movement of the operating handle 6 in the counter-clockwise direction, a corresponding movement of the lower control drum 2 is effected through the agency of the lug 24, and any

55 desired forward or backward movement of the control drum 2 may be effected by merely actuating the handle 6 in a corresponding manner. During such operation, the upper lug 14 of the rod 5 travels within the in-

60 terior drum slot 12 and the corresponding slot in the wall of the hollow shaft 3, so that no normal movement of the drum 1 occurs, while the presence of the stop 26 completely prevents any accidental move-

ment of the drum 1 in the counter-clockwise 65 direction.

I do not wish to be restricted to the specific structural details or arrangement of parts herein set forth, as various modifications thereof may be effected without departing from the spirit and scope of my invention. I desire, therefore, that only such limitations shall be imposed as are indicated in the appended claims.

75 I claim as my invention:

1. A control apparatus embodying a plurality of movable contact-carrying members, means for rendering the movement of said members mutually exclusive and for selectively controlling the movements of said 80 members, and a common handle member for moving either of said members substantially without change in its own initial location.

2. A control apparatus embodying a plurality of movable contact-carrying members, 85 means for rendering the movement of said members mutually exclusive, a common handle member for moving either of said members substantially without change in its own initial location, and biasing means for normally effecting mechanical connection of said handle member to a certain movable member.

90 3. A control apparatus for electrical systems embodying a plurality of movable contact-carrying members, a shaft loosely associated therewith, and adjustable means for determining which movable member shall be actuated by movement of said shaft.

95 4. A control apparatus for electrical systems embodying a plurality of movable contact-carrying members, a shaft loosely associated therewith, means normally operatively engaging said shaft and one of said movable members, and means for causing 100 said first means to operatively engage said shaft and another movable member.

105 5. A control apparatus embodying a plurality of movable drums, a shaft loosely associated therewith, means biased to normally operatively engage said shaft and one 110 of said drums, and means for effecting disengagement from that drum and engagement with said shaft and a second drum.

115 6. A control apparatus embodying a plurality of movable drums, a shaft loosely associated therewith, means biased to normally operatively engage said shaft and one of said drums to effect rotative movement thereof in the one direction, and means for 120 effecting mutually exclusive engagement with said shaft and a second drum to effect rotative movement thereof in the opposite direction.

125 7. A control apparatus for electrical systems embodying a plurality of rotatable contact-carrying drums, a hollow shaft loosely associated therewith, and a rod ex-

- tending through said shaft and adapted to adjustably engage said shaft and the one or the other of said drums.
8. A control apparatus embodying a plurality of rotatable drums severally having interior annular slots, a hollow shaft loosely inclosed by said drums and having correspondingly located side slots, a rod extending through said shaft and having a plurality of side lugs, and means for causing the one or the other of said lugs to engage a portion of the corresponding interior slot to thereby permit actuation of the one or the other drum by said shaft.
9. A control apparatus embodying a plurality of rotatable drums having interior annular slots respectively provided with an upwardly-extending and a downwardly-extending recess, a hollow shaft loosely inclosed by said drums and having correspondingly located side slots, a rod extending through said shaft and having a plurality of side lugs, and means for causing the one or the other of said lugs to engage the corresponding recess to thereby permit actuation of the one or the other drum by said shaft in opposite directions.
10. A control apparatus embodying a plurality of rotatable drums having interior annular slots respectively provided with an upwardly-extending and a downwardly-extending recess, a hollow shaft loosely inclosed by said drums and having correspondingly located side slots, a rod extending through said shaft and having a plurality of side lugs, a spring for normally biasing one of said lugs into engagement with the corresponding recess to produce rotative movement of the correspond-
- ing drum in the one direction, and means for causing the other lug to engage the other recess to effect rotative movement of the other drum in the opposite direction.
11. A control apparatus embodying a pair of movable contact members, means for exclusively moving either of said members upon the actuation of said means from the same initial location and means for selectively controlling the operative connection of said moving means to the one or the other of said members.
12. In combination, a pair of members having central, longitudinally-aligned openings and annular, interiorly-disposed slots provided with offset recesses connecting therewith, said recesses being oppositely disposed, and a shaft rotatively mounted in said openings and having lugs for coöperating with said slots and said recesses to cause either of said members and said shaft to rotate together, one of said lugs occupying one of said slots when said other lug occupies one of said recesses and said one lug occupying said other slot when said other lug occupies said other recess.
13. A control apparatus embodying a plurality of longitudinally-aligned contact-carrying drums rotatably mounted upon a shaft, means for rendering the movement of said drums mutually exclusive and a common handle member for moving either of said drums by actuating said handle from the same initial position.
- In testimony whereof I have hereunto subscribed my name this 2nd day of Jan., 1917.

THOMAS C. WURTS.
